Manuel Block

UNITED STATES PATENT OFFICE

RONALD TASHOFF, OF BROOKLYN, NEW YORK

SCARF RING

Application filed June 1, 1931. Serial No. 541,207.

This invention relates to clasps, clamps or rings, adapted for use in conjunction with wearing apparel such as scarfs and the like that usually require to be fastened by knotting.

One of the objects of the invention is to provide such a clasp or ring that will clamp the tie or the like in such a manner as to form a knot simulating portion without having to actually tie the said scarf to form a knot.

Another object of the invention is to provide a scarf ring of the nature referred to, comprising a main body portion, a ring segment pivotally secured to the said body portion, and clasping or locking means on both the body portion and segment for securing the said ring about the scarf.

A further object of the invention is to provide such a ring with an ornamental geometric clasp or lock at the front thereof.

Another object is to produce a device of the character described in which the maximum simplicity of construction and operation is secured.

Other objects and advantages will appear as the nature of the improvements is better understood, the invention consisting substantially in the novel arrangement and co-relation of parts herein fully described, and illustrated in the accompanying drawings, wherein similar reference characters are used to describe corresponding parts throughout the several views, and then finally pointed out and specifically defined and indicated in the appended claims.

The disclosure made the basis of exemplifying the present inventive concept suggests a practical embodiment thereof, but the invention is not to be restricted to the exact details of this disclosure, and the latter, therefore, is to be understood from an illustrative rather than a restrictive standpoint.

The inventive idea involved is capable of receiving a variety of mechanical expressions, one of which, for the purpose of illustration, is shown in the accompanying drawings, in which

Figure 1 is a front view of a portion of a scarf or necktie showing one form of my knot forming ring as applied thereto.

Figure 2 is a top plan view of the ring, showing same in opened position in dot and dash lines.

Figure 3 is a side view of the ring and

Figure 4 is a front elevation of a modified form of the invention.

In knotting a four-in-hand tie, one end of the tie is wrapped around the other end, and then brought upward and threaded through the folds formed by the wrapping and finally tightened. All this consumes considerable time and requires skill to form a neat appearing knot. Constant tying and untying of the knot causes the tie to become wrinkled, soiled and worn. To obviate these undesirable features, I have perfected my new and improved scarf ring.

Referring now to the drawings in detail 5 indicates a four-in-hand necktie or scarf, the larger end 6 of which is wrapped around the smaller end 7 and looped over the top thereof and permitted to hang down without tying.

To form a knot simulating portion 8, I pass the open ring 9 around the tie, close same and adjust it to the required position on the tie.

The ring 9 comprises a shank or body portion 10 preferably made of an upper wire member 11 soldered along its lower surface to the upper surface of a lower wire member 12. The upper wire member 11 terminates in an end 13 and the lower member 12 in a scroll 14. The opposite ends of the wires 11 and 12 are formed into a reduced hinge portion or ear 15 upon which is pivotally mounted by means of a pin 17 a segment or gate 16 comprising a lower wire member 22 and an upper wire member 18 which terminates at the front thereof in a complementary scroll 19 adapted to snap into the scroll 14 and have locking engagement therewith at 20 and 21 (see Fig. 1). The lower wire member 22 terminates at the front thereof in an end 23, which end and the end 13 abut portions of the scrolls 14 and 19 respectively in locking engagement.

In Fig. 4, I have shown a modified form of the invention wherein I employ rectangular portions 25 and 26 forming my clasp or lock.

Various other geometrically formed clasps or locks may be used if desired.

From the foregoing it will be seen that I have provided a simple and efficient tie ring adapted to form a knot simulating portion on a tie without actually knotting the tie, and thus prevent the soiling and wearing of same.

Having described my invention what I claim as new and desire to secure by Letters Patent is:

- 10 1. A scarf ring, comprising a shank portion, a loop-like locking portion thereon, a gate pivotally secured to the said shank, and a loop-like locking portion on the said gate for the purpose specified.
- 15 2. A scarf ring, comprising an upper and lower wire member, a gate of similar construction pivotally secured to the shank at one end thereof, a geometric locking portion on one of the shank wires at the end opposite to the pivot and a complementary geometric portion on the oppositely disposed gate wire adapted to lockingly engage the first mentioned geometric portion.
- 20 3. A scarf ring, comprising an upper and lower wire member, a gate of similar construction pivotally secured to the shank at one end thereof, a geometric locking portion on one of the shank wires at the end opposite to the pivot, a complementary geometric portion on the oppositely disposed gate wire adapted to lockingly engage the first mentioned geometric portion, an end on one of the shank wires abutting the geometric end of the gate when in closed position, and a similar end on one of the gate wires in abutment with the geometric end of the shank.

RONALD TASHOFF.
